Patented Nov. 11, 1919.

3 SHEETS—SHEET 3.

A detailed technical drawing of a mechanical assembly, labeled 'Fig. 4. 50' at the top. The assembly consists of a vertical column with various components. At the top, a horizontal plate with a central slot is shown. A vertical rod 29 passes through this slot. A horizontal plate 31 is attached to the top of the rod 29. A vertical plate 30 is positioned to the right of the rod 29. A horizontal plate 14 is attached to the right side of the vertical plate 30. A vertical plate 11 is attached to the left side of the vertical plate 30. A horizontal plate 48 is attached to the left side of the vertical plate 11. A horizontal plate 47 is attached to the top of the vertical plate 11. A horizontal plate 35 is attached to the top of the vertical plate 47. A horizontal plate 36 is attached to the top of the vertical plate 35. A horizontal plate 45 is attached to the top of the vertical plate 36. A horizontal plate 41 is attached to the top of the vertical plate 45. A horizontal plate 43 is attached to the top of the vertical plate 41. A horizontal plate 44 is attached to the top of the vertical plate 43. A horizontal plate 54 is attached to the left side of the vertical plate 44. A horizontal plate 32 is attached to the bottom of the vertical plate 44. A horizontal plate 27 is attached to the right side of the vertical plate 32. A horizontal plate 1 is attached to the left side of the vertical plate 27. A horizontal plate 52 is attached to the bottom of the vertical plate 1.

UNITED STATES PATENT OFFICE.

GIUSEPPE ALFANO, OF NEW YORK, N. Y.

ELEVATOR-DOOR AND OPERATING MECHANISM THEREFOR.

1,321,697.

Specification of Letters Patent.

Patented Nov. 11, 1919.

Application filed May 25, 1917. Serial No. 171,058.

To all whom it may concern:

Be it known that I, GIUSEPPE ALFANO, a subject of the King of Italy, residing at New York city, in the county of New York 5 and State of New York, have invented new and useful Improvements in Elevator-Doors and Operating Mechanism Therefor, of which the following is a specification.

This invention relates to elevator doors 10 and operating mechanism therefor, and one of the objects is to provide means of certain novel construction for controlling the door of an elevator cage and for simultaneously controlling the shaft doors.

15 A further object is to provide for automatically controlling a collapsible cage door or plurality of doors and a shaft door or plurality of doors.

A further object is to provide for controlling a cage door or pair of doors and automatically collapsing a shaft door and turning the latter in an outward direction.

A still further object is to provide for automatically and simultaneously controlling the cage door or doors and the shaft doors, and for turning the doors last mentioned in an outward direction in the same operation, providing an unobstructed entrance to the elevator cage.

30 With the foregoing and other objects in view, the invention consists in the novel construction, combination, and arrangement of elements hereinafter described and claimed.

35 In the drawings:

Figure 1 is a view of the shaft doors in front elevation and showing also a similar elevation of the cage doors.

Fig. 2 is a transverse section showing the 40 means for controlling the frame carrying the cage doors, the section being on line 2-2 of Fig. 1.

Fig. 3 is a view partly in horizontal section and showing in top plan a tripper for 45 controlling the doors of the cage.

Fig. 4 is a front elevation showing the shaft doors at one side collapsed and thrown outwardly.

Fig. 5 shows the same structure looking 50 from the right in Fig. 4.

Fig. 6 is a detail partly in elevation and partly in vertical section showing in detail the means for controlling the frames in which the collapsible doors are mounted, the 55 section being on line 6-6 of Fig. 1.

Fig. 7 is a detail in elevation showing

means whereby two shaft doors, one above the other, are simultaneously operated.

Fig. 8 shows the cage doors on one side of the doorway in collapsed position.

Fig. 9 is a detail in elevation showing the tripper controlling the cage doors, and certain of the adjacent structure.

Fig. 10 is a section on the line 10-10 of Fig. 9.

Fig. 11 is a detail view of one of the channeled members coöperating with the tripper of Fig. 9.

The mechanism for mounting and controlling the shaft doors will first be described in connection with the construction of these doors.

Mounted on opposite sides of the shaft and adjacent to the doorway forming an entrance to the cage are a plurality of stationary vertical shafts designated 10 and 11, and pivotally or hingedly mounted on each of these shafts are frames 12 and 14 in which the shaft doors are supported. Each frame carries a plurality of doors 15 and 16, the 75 doors of oppositely located frames coöperating with each other to close the shaft opening along a central vertical line. Each shaft door comprises a plurality of members 17, 18 and 19, which are located in a 80 horizontal position when the doors are in their closed position,—that is in the position for protecting the shaft opening. Bars 17, 18 and 19 have pivotal connection with bars 20, 21 and 22 extending at an angle 90 with the bars first mentioned, and the horizontally extending bars may be offset at their outer ends at a point adjacent to the pivotal mounting.

The lower bars of the upper doors are 95 each provided with toothed members or pinions 23 rigidly mounted with reference to said bars and adapted to mesh with pinions 24 carried by the upper bars of the lower doors. The pivotal mounting of these 100 pinions is shown at 25 and 26 and the pivotal mounting of the other bars of said doors is designated 27. The pivot members pass through the side bars 29 and 30 of each frame 12 and 14, and said frames are pivotally or hingedly connected with vertical shafts 10 and 11 by means of apertured bracket members 31 and 32.

The pivot member 26 is provided on one end with a beveled pinion 35 meshing 110 with a pinion 36 keyed to each vertical shaft 10 and 11. An apertured bracket 38 is sup-

ported on a vertical bar 39 secured to the shaft structure, and within this bracket is mounted a sleeve 40, carrying at its lower end a gear wheel 41 and having fixed connection at its upper end with a bracket 42 secured to the frame on which the door is mounted. Gear wheel 41 is rigidly connected with said frame, as indicated at 43, and rotates the frame on the shaft 11, the 10 frame being held in normal position by spring 44.

Meshing with gear wheel 41 is a gear wheel 45 mounted on a short shaft 46 and adapted to have rotary movement imparted 15 thereto by means of a tripper 47 coöperating with a channel member 48 which is movable with the cage, and is provided with an inwardly flared portion 49, the flared portions of oppositely located members 48 converging 20 with reference to each other. A stationary vertical guiding member or bar 50 is mounted in the shaft at each side and coöperates with channel member 48. The upper portions of oppositely located channels 48 may be connected by means of transverse bar 52, carried by the cage and offset at the points 53, and the lower ends of channels 48 are similarly connected by means of a bar 54 having its end portions offset at 55. 30 The transverse bars mentioned are secured to the cage at points above and below the doorway.

Upon the movement of the cage to a proper position, the channels 48, or the end 35 portions thereof, engage the trippers 47 and rotate beveled gear wheels 45 and 41, transmitting rotary movement to the frame or frames carrying the collapsible doors. This rotary movement of the frame causes the rotary movement of gear wheel 35, in view of 40 the fact that the latter meshes with gear wheel 36 on the shaft and that said gear wheel 35 is mounted on the rotary frame and therefore moves about the axis of stationary 45 wheel 36. The movement imparted to gear wheel 35 causes the movement of pinions 23 and 24, thereby collapsing the doors of the shaft at the time they are moved outwardly, the two operations being practically simultaneous.

The doors of the cage are similarly arranged and constructed, two of these doors on a given side of the shaft being referred to in the following description, and these doors 55 being designated 60 and 61. The doors 60 and 61 on a given side of the cage are operated by means of a tripper 62 coöperating with a channel 63, the open side of the channel facing toward the interior of the shaft. 60 The end portions of the inner channels are deflected toward each other, and they are engaged by the tripper upon movement of the cage to a position opposite the doorway of the shaft. The tripper 62 is carried on 65 a short shaft 64 mounted between the sta-

tionary vertical bars 65 and 66 carried by the cage, and said shaft 64 acts under the influence of a spring 67 to hold the doors normally in a position to close the doorway of the cage. A similar spring 68 acts in the same manner with reference to the doors of the shaft, although the spring last named acts directly to rotate the door frames and then to operate the doors. 70

The shaft 64 carries a pinion 72 which 75 meshes with a pinion 73, and these pinions are rigid with reference to the upper and lower bars of the respective doors, whereby their rotation serves to collapse these doors in the manner indicated in connection with the doors of the shaft. It will be understood that the trippers operate to control the doors as the cage approaches the shaft opening and before it is immediately opposite 80 said opening. 85

What is claimed is:

1. In a device of the class described, a cage, a door therefor, means on the cage adapted to be engaged by means in the shaft for automatically operating the door, a rotatable and collapsible shaft door, and cage operated means for rotating and collapsing the shaft door. 90

2. In a device of the class described, a cage, a door therefor, means on the cage adapted to be engaged by means in the shaft for automatically operating the door, a collapsible shaft door mounted for movement on a vertical axis, and cage operated means for imparting a plurality of independent 100 movements to the shaft door for opening the latter. 95

3. In a device of the class described, a cage, a door therefor, a rotatable and collapsible shaft door, and a plurality of rotatable devices each controlled by the movement of the cage for operating said doors simultaneously, said rotatable devices each including meshing gear wheels and a rotatable trip imparting movement thereto. 105

4. In a device of the class described, a cage, a door therefor, a pair of shaft doors, each of said doors being collapsible, and means controlled by the movement of the cage for operating said doors simultaneously and a second pair of collapsible shaft doors, 115 and means for collapsing the second pair upon the collapse of the doors of the pair first named.

5. In a device of the class described, a cage, a door therefor, a shaft door, each of said doors being collapsible and one of said doors mounted for movement outwardly, and means for effecting all of said movements automatically by the movement of the 120 cage. 125

6. In a device of the class described, a cage, a door therefor, a shaft door, each of said doors being collapsible and one of said doors mounted for movement outwardly, 130

and means for effecting all of said movements simultaneously by the movement of the cage.

7. In a device of the class described, a cage, a collapsible door therefor, means for automatically collapsing the door, a collapsible shaft door, and cage operated means for automatically collapsing the door last named and turning the same outwardly 10 upon the collapse of the door first named.

8. In a device of the class described, a cage, a collapsible door therefor, means engaging the door for automatically collapsing the latter, a shaft door, means for 15 mounting the same to produce partial rotation, and means for effecting such partial rotation upon the collapse of the door first named.

9. In a device of the class described, a cage, a collapsible door therefor, a rotary collapsible shaft door, mounting means therefor, means for collapsing said door and means for opening the shaft door automatically by a partial rotary movement upon 25 the collapse of the door first named.

10. In a device of the class described, a cage, a collapsible door therefor, a collapsible shaft door, spring held mounting means therefor, means for collapsing said door 30 and means for opening the shaft door automatically upon the collapse of the door first named.

11. In a device of the class described, a cage, a collapsible door therefor, spring held mounting means for said door, a shaft 35 door, spring held rotary mounting means for the latter, and devices operated by movement of the cage for producing the simultaneous opening of both doors.

40 12. In a device of the class described, a cage, a collapsible door therefor, means holding said door normally closed, a collapsible shaft door rotatably mounted, means holding the latter normally closed, 45 means for collapsing the door last named and partly rotating the mounting means therefor.

13. In a device of the class described, a cage, a door therefor, a collapsible shaft 50 door, a frame for mounting the latter, a vertical shaft, means for partly rotating the

frame on the shaft by the movement of the cage, and means for simultaneously collapsing the door last named.

14. In a device of the class described, a cage, a door therefor, a shaft door, means for holding the shaft door normally closed, a channel member and a tripper engaging the channel member, a vertical frame for mounting said door, a vertical shaft about 60 which the frame is partly rotatable, and means for rotating the frame by the tripper and throwing the door outwardly.

15. In a device of the class described, a cage, a door therefor, a pair of collapsible 65 shaft doors, mounting means for the doors last named, rotatable on a vertical axis, meshing pinions carried by certain of the members of said doors, and means for rotating the pinions for collapsing the doors 70 and simultaneously causing the rotary movement of the mounting means on a vertical axis.

16. In a device of the class described, a cage, a door therefor, a pair of collapsible 75 shaft doors, mounting means for the doors last named, meshing pinions carried by certain of the members of said doors last named, a vertical shaft about which the mounting means is rotatable, resilient 80 means retaining the mounting means in normal position, a tripper, gearing transmitting motion from the tripper to the mounting means, and gearing transmitting motion to one of the pinions and thence to 85 the other of said pinions.

17. In a device of the class described, a cage, a door therefor, a pair of collapsible shaft doors including a plurality of members pivotally connected and a rotatable 90 frame for mounting the same, meshing pinions carried by certain of the members of the respective doors, a vertical shaft about which the frame is rotatable, resilient means retaining the shaft in normal position, a tripper, gearing, mounting means therefor, said gearing transmitting motion from the tripper to the frame, and gearing transmitting motion to one of the pinions and thence to 95 the other of said pinions.

100 In testimony whereof I affix my signature.
GIUSEPPE ALFANO.
